UNITED STATES PATENT OFFICE.

MARY E. PHOEBUS AND MARGARET NATALIE PHOEBUS, OF BROOKLYN, NEW YORK.

DESIGN FOR A MEMORIAL HONOR-BAND.

52,752.

Specification for Design.

Patented Dec. 10, 1918.

Application filed March 28, 1918. Serial No. 225,361. Term of patent 3½ years.

To all whom it may concern:

Be it known that MARY E. PHOEBUS and MARGARET NATALIE PHOEBUS, both citizens of the United States, residing at Brooklyn, in the county of Kings and State of New York, have invented a new, original, and ornamental Design for a Memorial Honor-Band, of which the following is a specification, reference being had to the accompanying drawing, forming part thereof.

The figure in the drawing is a plan view of a memorial honor band, showing our new design with the ends broken away.

We claim:

The new, original and ornamental design for a memorial honor band as shown with the ends broken away.

MARY E. PHOEBUS,
MARGARET NATALIE PHOEBUS.
